(57) CLAIM

We claim the ornamental design for a footwear upper, as shown and described.

DESCRIPTION

The patent or application file contains at least one drawing executed in color. Copies of this patent or patent application publication with color drawing(s) will be provided by the Office upon request and payment of the necessary fee.

FIG. 1 is a photographic front perspective view of a footwear upper;

FIG. 2 is a right side view thereof;

FIG. 3 is a left side view thereof;

FIG. 4 is a front view thereof;

FIG. 5 is a rear view thereof; and,

FIG. 6 is a top view thereof.

1 Claim, 6 Drawing Sheets

(6 of 6 Drawing Sheet(s) Filed in Color)
